UNITED STATES PATENT OFFICE.

ANDREW SCHEAFFER, OF DETROIT, MICHIGAN.

WHEEL-HARROW.

SPECIFICATION forming part of Letters Patent No. 292,955, dated February 5, 1884.

Application filed August 1, 1883. (No model.)

To all whom it may concern:

Be it known that I, ANDREW SCHEAFFER, of Detroit, in the county of Wayne and State of Michigan, have invented new and useful 5 Improvements in Harrows; and I do hereby declare that the following is a full, clear, and exact description thereof, reference being had to the accompanying drawings, which form a part of this specification.

10 This invention relates to certain new and useful improvements in two-wheeled harrows; and the novelty consists in the peculiar construction and arrangement of parts, as will be more fully hereinafter set forth, and specifically pointed out in the claims.

Figure 1 is a plan view of my improved machine. Fig. 2 is a perspective view of the main and supplemental frame with traction-wheels and harrow-teeth removed. Fig. 3 is a vertical central section of Fig. 1. Fig. 4 is a detached perspective of the locking device for the sliding frame. Fig. 5 is a detached perspective of one of the harrow-teeth provided with the cultivator-shovel attachment. Fig. 25 6 is a detached perspective of one of the cultivators.

In the accompanying drawings, A represents an arched axle, provided near each end with the vertical arms *a*, the lower ends of 30 which terminate in the axle-arms *b*, upon which are mounted suitable traction-wheels. The vertical portions *a* of the axle A work between side guides, *b'*, of the guide-boxes B, upon the two outer sides of the frame C, and through the 35 top of these boxes B are threaded set-screws D, the lower ends of which come in contact with the upper edge of the axle, and by means of which the said frame C is adapted to be vertically adjusted upon the axle, as may be desired. Across the bottom of the frame C are secured the bars E, to the rear faces of each of 40 which are pivotally secured, in any convenient manner, the harrow-teeth F. The lower points of these harrow-teeth are cut back, and 45 provided with a cutting-edge, *c*, while the upper ends project upward between the transverse bars of the frame G, which has a sliding movement upon the upper edge of the frame C. The longitudinal bar H of the frame G is 50 connected by means of a rod, I, to the lever J, which is pivotally secured to the rear girt of the frame C, and this lever J is provided

with the spring-pawl K, which engages with the notched quadrant L upon the frame C. By this arrangement of parts, when the frame G is drawn back by means of the lever it allows the harrow-teeth to drop or lower and come in contact with the surface of the ground, while it does not rigidly hold them to such position, there being a slight play to the teeth, 60 so that they may pass over obstructions. When the frame G is advanced or slid forward toward the front end of the frame C, the cross-bars of the frame G press against the upwardly-projecting portions of the harrow-teeth and 65 raise them out of the ground. When the frame is in its rearward extension, or so that the harrow-teeth rest upon the ground, the sliding frame is locked to such position by means of a locking-bar, M, the ends of which are provided with semicircular springs N, which have a vertical movement in suitable guides, *m*, on the inside of the side bars of the frame C. Pivotedly secured to this locking-bar M is a lever, O, which is pivotally secured to one of 75 the cross-bars of the frame C, while its rear end is received in the bifurcated end of a rock-lever, P, pivotally secured to the rear girt of the frame C, while the opposite end of this lever P is connected, by means of a link, R, to one 80 end of the arm S, which is secured rigidly to the lever J in such manner that as the frame is brought back, so as to allow the teeth to drop, and is locked by the lever J, the springs N are, by the connections hereinbefore named, 85 elevated or raised in front of the front ends of the side bars of the frame G, which locks the frame with a yielding force, and thus prevents wabbling thereof, as will be readily understood.

At the rear of the device I secure a seat, T, which brings the driver within easy reach of the operating-levers, the draft being applied at the opposite end by means of a pole, V, or a pair of shafts, as may be desired.

In Fig. 6 I show a cultivator-tooth or mold-board, W, which is provided with a socket, *h*, upon its inner face, which can readily be secured upon the harrow-teeth by means of a screw, *i*, which will readily transform the harrow into a cultivator. Should the teeth of the harrow be so arranged that any of them would come in contact with the plants that it is desired to cultivate, such tooth (particularly in

the longitudinal center of the device) can readily be removed, when, by using two horses, the device would straddle one row, while it would readily cultivate three.

5 What I claim as my invention is—

1. The frame C, having transverse bars E, and the teeth F, pivoted to such bars E, and having their upper ends projecting between the bars of the sliding frame G, the spring 10 locking device M N, the said sliding frame G, and means, substantially as described, for manipulating all the teeth simultaneously, and for locking the frame G in its rearward position with the teeth in operation, as set forth.
- 15 2. In combination with the frame C, bar

row-teeth F, and sliding frame G, constructed substantially as described, the locking device M N, adapted to be elevated and depressed simultaneously with the movements of the sliding frame by means of the levers O and P and 20 connections with the lever operating the sliding frame, substantially as specified.

3. In combination with the frame C, teeth F, frame G, rod I, lever J, and quadrant L, the levers O P, link R, arm S, and springs N, substantially as described. 25

ANDREW SCHEAFFER.
